UNITED STATES PATENT OFFICE.

TEIJI KOTATO, OF NEW YORK, N. Y.

DESIGN FOR A PLATE OR SIMILAR ARTICLE.

Application filed February 23, 1924. Serial No. 8,704. Term of patent 7 years.

To all whom it may concern:

Be it known that I, TEIJI KOTATO, a subject of the Emperor of Japan, residing in the city, county, and State of New York, have invented a new, original, and ornamental Design for Plate or Similar Article, of which the following is a specification, reference being had to the accompanying drawing, forming part hereof.

Figure 1 is a plan view of one of the pieces, to wit, the dinner plate of a dinner set showing my new design, it being under-

stood that the design shown in this figure is to be repeated entirely around the plate.

Figure 2 is a fragmentary portion of the plate with the ornamental border design somewhat enlarged. It is understood that the complete design involves a mere repetition or continuation of the ornamental border, partially shown in the several views.

I claim:

The ornamental design for a plate or similar article, as shown.

TEIJI KOTATO.
